UNITED STATES PATENT OFFICE

2,445,942

CANE

George B. Dusinberre, Wichita, Kans.

Application January 31, 1947, Serial No. 725,591

3 Claims. (Cl. 135—47)

1

This invention relates to walking sticks or canes, particularly for the use of the blind, and in particular includes a walking stick having a crook forming a handle at the upper end and a roller in the lower end wherein the roller may be held stationary by a brake normally held in releasing position by a spring and adapted to be applied by a trigger on the handle.

The purpose of this invention is to provide an aid for the blind that may be rolled along ahead of the individual to warn the user of obstructions, such as curbs, steps and the like, and which is provided with means for holding the roller stationary to aid the user in going up and down steps and the like.

Because of unevenness of walks and the like, a blind person cannot run a cane along ahead of him, and for this reason is continuously tapping the walk or ground as he travels ahead. With this thought in mind, this invention contemplates a cane having a roller or wheel in the lower end wherein the end of the cane may readily be run along ahead of the user to eliminate the necessity of tapping and the like.

The object of this invention is to provide means for incorporating a roller or wheel in the end of a cane with means for locking or releasing the roller from the upper end of the cane without adding materially to the weight of the cane.

Another object of the invention is to provide means for incorporating a roller or wheel in the end of a cane with braking means associated therewith wherein substantially all of the additional weight added by the actuating parts is located in the lower end of the cane.

Another object of the invention is to provide means for incorporating a roller with a manually controlled brake in the end of a cane without enlarging the size of the cane.

Another object of this invention is to provide means for incorporating a roller with a manually controlled brake therefor in a cane without making the appearance of the cane objectionable.

A further object of the invention is to provide means for incorporating a roller with a manually controlled brake in a cane in which the cane with the operating instrumentalities associated therewith is of a simple and economical construction.

With these and other objects in view, the invention embodies a tubular cane having a crook at the upper end forming a handle, a socket with depending downwardly extending arms having a rubber tired roller rotatably mounted in the lower ends of the arms, a brake in the socket posi-

tioned to contact the surface of the roller, a spring in the socket urging the brake away from the roller, a trigger pivotally mounted in the upper end of the cane, and an actuating rod connecting the trigger to the brake through the tubular element of the cane.

Other features and advantages of the invention will appear from the following description taken in connection with the drawings, wherein:

Figure 1 is a view showing a side elevation of the cane with parts broken away.

Figure 2 is a view showing an end elevation of the cane also with parts broken away.

Figure 3 is a detail showing a cross-section through the lower part of the cane with the lower ends of the socket and roller broken away, and with the upper portion of the cane also broken away.

Figure 4 is a detail showing the upper end of the tubular element of the cane with the handle omitted and with parts broken away showing the mounting of the trigger therein.

Referring now to the drawings, wherein like reference characters indicate corresponding parts, the roller cane of this invention includes an elongated tubular element 10, a roller 11 and a trigger 12.

The tube 10 may be provided as shown with threads 13 at the upper end upon which a handle 14 may be threaded, as shown in Figure 1, and the lower end may also be provided with threads 15 upon which a socket 16 may be screwed, as shown. The socket 16 is formed with downwardly extending arms 17 and 18, which have hubs 19 and 20 at their lower ends in which the roller 11 is rotatably mounted on a bolt 21. The roller 11 is provided with a tire 22 of rubber or other resilient material, and in the upper part of the socket is a brake element 23 having a groove 24 in the lower surface

thereof adapted to contact the outer surface of the tire 22. The brake 23 is secured on the lower end of a rod 25 by a screw 26, and with a tension spring 27 positioned around the rod with one end of the spring secured to a washer 28 and the other held on the screw 26, the brake will be resiliently held upward so that the roller is released.

When it is desired to hold the roller stationary, the trigger 12 is pulled upward by the forefinger of a hand around the handle, and being pivotally mounted

on a pin 29 in extending ears 30, and with the inner end thereof pivotally connected through a socket 31 and a pin 32 to the upper end of the rod 25, the rod will be forced downward clamping the brake against the wheel.

The washer 28 is held in clamping relation

against a shoulder 33 in the socket 15 by the lower end of the tube 10 and the lower end of the rod 25 is slidably held in an opening 34 in the center of the washer.

In the roller cane of this invention a freely rotatable roller is provided at the lower end so that a blind person may roll the cane along ahead of him to feel the terrain, and when it is desired to use the device as a support in going up and down steps, the user may draw the trigger upward so that the roller may be clamped stationary, as illustrated and described.

It can be appreciated that the cane may be provided in different designs, and modifications may be made in the design or arrangement of the parts without departing from the spirit of the invention.

What is claimed is:

1. In a walking stick, a tubular staff, a socket with downwardly extending arms mounted on the lower end of the staff, a wheel rotatably mounted in the lower ends of said downwardly extending arms, a braking element slidably mounted in the socket positioned to contact the surface of the roller, means resiliently urging the braking element away from the roller, a trigger pivotally mounted in the upper end of the staff, and a rod pivotally connected to the trigger extending through the staff to the braking element adapted to be actuated by the trigger to move the braking element into contact with the roller for clamping action thereof.

2. In a walking stick, the combination, which comprises a tubular staff, a handle at the upper end of the staff, a socket with downwardly extending arms mounted on the lower end of the staff, a wheel positioned between the downwardly extending arms of the socket, means rotatably mounting the wheel in the lower ends of said arms, a braking element slidably mounted in the socket positioned to contact the surface of the wheel, a spring urging said braking element away

from the wheel, a rod upon which said braking element is mounted extending upward through the staff to a point at the upper end thereof, and a trigger pivotally mounted in the upper end of the staff pivotally connected to the rod extending upward from the braking element.

3. In a walking stick, the combination, which comprises an elongated tubular staff, a socket with downwardly extending arms threaded on the lower end of the staff, a roller positioned between the arms of the socket, means rotatably mounting the roller in the lower ends of the arms of the socket, said roller having a rubber tire, a block slidably mounted between the arms of the socket positioned to contact the surface of the roller, a washer clamped against a shoulder in the socket by the lower end of the staff, a tension spring connected to the washer and block urging the block away from the roller, a centrally disposed rod extending upward through the tubular staff with the lower end connected to said block, a trigger pivotally mounted between extending ears at the upper end of said tubular staff with an extending handle on the exterior of the staff and with an operating extension extending into said tubular staff, means pivotally connecting the operating extension of the trigger to the upper end of said centrally disposed rod in the tubular staff, and a handle threaded on the upper end of the staff positioned so that the trigger may be engaged by the forefinger of a hand thereon.
